UNITED STATES PATENT OFFICE

127,579

DESIGN FOR A RADIO RECEIVING SET

Daniel J. Crowley, Grosse Pointe, Mich.

Application February 3, 1941, Serial No. 98,706

Term of patent 14 years

To all whom it may concern:

Be it known that I, Daniel J. Crowley, a citizen of the United States of America, residing at Grosse Pointe, in the county of Wayne and State of Michigan, have invented a new, original, and ornamental Design for a Radio Receiving Set, of which the following is a specification, reference being had to the accompanying drawing, forming a part thereof, wherein

Figure 1 is a side elevational view of my new design of radio receiving set; and

Figure 2 is a top plan view of the design shown in Figure 1 and showing the openings for the passage of sound in dotted lines.

I claim:

The ornamental design for a radio receiving set, substantially as shown.

DANIEL J. CROWLEY.
